UNITED STATES PATENT OFFICE.

JOHN McE. AMES, OF DONGAN HILLS, NEW YORK, ASSIGNOR TO AMERICAN CAR AND FOUNDRY COMPANY, OF ST. LOUIS, MISSOURI, A CORPORATION OF NEW JERSEY.

CAR-UNDERFRAME.

No. 879,396.

Specification of Letters Patent.

Patented Feb. 25, 1908.

Application filed November 21, 1907. Serial No. 403,195.

To all whom it may concern:

Be it known that I, JOHN McE. AMES, a citizen of the United States, and a resident of Dongan Hills, Staten Island, Richmond county, and State of New York, have invented certain new and useful Improvements in Car-Underframes, and do hereby declare that the following is a full, clear, and exact description of the invention, such as will enable others skilled in the art to which it appertains to make and use the same, reference being had to the accompanying drawings, forming part of this specification, in which—

Figure 1 is a plan view of one half of a car underframe equipped with the invention; Fig. 2 is a central longitudinal sectional view on line 2—2 of Fig. 1; Fig. 3 is an end elevational view; Fig. 4 is a transverse sectional view showing at the right hand portion a view taken on line 4—4 of Fig. 1 and at the left hand portion a view on line 5—5 of Fig. 1.

The object of the invention is to provide a combination wood and metal underframe for railway cars wherein center sills, side sills and intermediate sills of wood are used in combination with draft sills of metal, preferably in relatively the plane of the car body bolster, extending from end to end of the car while needle beams, recessed to receive said draft sills, with queen posts and truss rods coöperate to support the load and transmit buffing and pulling stresses.

In the drawings 5 indicates the center sills; 6 intermediate sills; 7 side sills; 8 end sills and 9 bolsters all according to standard construction said longitudinal sills being of wood and being preferably continuous from end sill to end sill. The bolster may be of any convenient type but for convenience I have illustrated a bolster having compression member 11, tension member 12 and struts 13 above the side bearings 14 and fillers 15 between the upper and lower flanges 16 of the rolled draft sill members 17, the said draft sills being continuous and serving, with the fillers 15, as struts for said bolsters while castings 18 are connected to the webs of said draft sills and extend longitudinally thereof at each side of said bolsters, as best shown in Fig. 2, the said castings rising to the plane of the top of said bolster so as to serve as stops for said draft sills whereby buffing and pull-

ing stresses are transmitted to said bolster. The castings 18 are unitary members having middle portions which are perforated for rivets 19 which secure said castings to the webs of the draft sills and have upwardly and downwardly projecting extensions 20—21 between which rest the upper and lower members of the bolster.

At convenient distances apart are tie plates 22 and 23 respectively above and below said draft sills and bolts 24 are passed through said tie plates, the flanges of said draft sills and through the center sills thereby securing said members together. Needle beams 25 extend transversely below the longitudinal sills and are recessed as shown in Fig. 4 (left) for the reception of the draft sills while queen posts 26 with lateral flanges 27 are secured below said needle beams by means of bolts 28 which pass through said flanges 27, the needle beams 25, the flanges 16 of said draft sills, through cover plates 29—let into recesses in said needle beams and center sills—and through said center sills whereby said parts are secured in position. The struts or queen posts 26^a below the intermediate sills and side sills are bolted in position by bolts 30 as shown.

It will be observed that the recesses in the needle beams are deeper than are the draft sills which pass through said recesses, whereby the said needle beams serve as supporting cross bearers for the longitudinal sills independently of said draft sills. This is important in a combined wood and metal underframe as it permits shrinkage of the wood members without subjecting the draft sills to compression in supporting the load.

What I claim is:

1. In a car-underframe, the combination comprising longitudinal sills, continuous draft sills of channel form disposed below said longitudinal sills, a needle beam recessed for said draft sills, a cover plate over said draft sills and needle beam, and secured to both sills.

2. In a car-underframe, the combination comprising longitudinal sills, continuous draft sills of channel form disposed below said longitudinal sills, a needle beam recessed in its upper portion for said draft sills, queen posts secured to said needle beam, a cover

plate over said draft sills and needle beam and bolts connecting said cover plate, draft sills and queen posts.

3. In a car underframe, the combination comprising longitudinal sills, continuous draft sills coextensive therewith, said draft sills comprising channels with wide horizontal flanges, a needle beam with recesses in its upper portion for said channels, and a cover plate secured to said draft sills and needle beam.

4. In a car underframe, the combination comprising longitudinal sills, bolsters and draft sills in a substantially uniform plane below said longitudinal sills, needle beams recessed for said draft sills and a cover plate connected to said draft sills and needle beam.

5. In a car underframe, the combination comprising longitudinal sills, bolsters and draft sills in a substantially uniform plane below said longitudinal sills, needle beams recessed for said draft sills, a cover plate connected with said needle beam and draft sills and stops on said draft sills adapted to abut against said bolsters.

6. In a car underframe, the combination comprising continuous center sills, recessed needle beams therebelow and continuous draft sills in the recesses of said needle beams.

7. In a car underframe, the combination comprising needle beams extending from side sill to side sill, draft sills resting in recesses in said needle beams, cover plates above said draft sills, queen posts with lateral flanges under said needle beams and bolts connecting said cover plate, draft sills, needle beams and queen posts.

8. In a car underframe, the combination comprising center sills, needle beams recessed in their upper portions, draft sills resting in said recesses, queen posts, truss rods, and cover plates above said draft sills and needle beams.

45 9. A combination wood and metal car underframe, comprising needle beams recessed in their upper portions, cover plates resting in said recesses, draft sills extending through said needle beams and means for connecting said cover plates, needle beams and draft sills.

10. A combination wood and metal car underframe, comprising needle beams recessed in their upper portions, cover plates resting in said recesses, flanged metal draft sills extending through said needle beams and means for connecting said cover plates, needle beams and draft sills.

11. A combination wood and metal car underframe, comprising needle beams recessed in their upper portions, cover plates resting in said recesses, channel shaped draft sills extending through said needle beams

and means for connecting said cover plates, needle beams and draft sills.

65

12. A combination wood and metal car underframe, comprising recessed needle beams, draft sills of channel shape resting in said recesses, cover plates for said draft sills and needle beams, flanged queen posts below said needle beams, bolts extending through said cover plates, draft sills and needle beams, bolsters, and stops on said draft sills coöperating with said bolsters.

13. In a combined wood and metal underframe, center sills, intermediate sills, side sills, recessed needle beams, cover plates resting in recesses in some of said members, continuous channel shaped draft sills with relatively wide horizontal flanges adapted to bear against said cover plates and said center sills and bolsters in relatively the plane of said draft sills.

14. In a combined wood and metal underframe, center sills, intermediate sills, side sills, recessed needle beams, cover plates resting in recesses in some of said members, continuous channel shaped draft sills with relatively wide horizontal flanges adapted to bear against said cover plates and said center sills, flanged queen posts and bolts passing through the flanges of said queen posts, said needle beams, the flanges of said draft sills, said cover plates and said center sills.

95

15. In a combined wood and metal car underframe, the combination comprising longitudinal sills, a bolster and continuous channel draft sills in relatively the same plane, and castings secured to the webs of said draft sills and rising at each side of said bolster to a plane beyond said draft sills thereby forming stops.

16. In a car underframe, the combination comprising longitudinal sills, flanged metal draft sills and a bolster in a relatively common plane below said longitudinal sills, said draft sills extending between members of said bolster and a casting secured to said draft sills, said casting extending to a plane beyond said draft sills thereby forming a stop coöperating with said bolster.

17. In a car underframe comprising wood center sills, independent metal draft sills in a plane below said center sills and a cross bearer partly below said draft sills and adapted to coöperate in supporting said center sills independently of said draft sills.

18. In a car underframe comprising wood center sills, independent metal draft sills in a plane below said center sills and a recessed cross bearer partly below said draft sills and adapted to coöperate in supporting said center sills independently of said draft sills.

19. In a car underframe comprising wood

125

center sills, independent flanged metal draft sills in a plane below said center sills and a recessed cross bearer partly below said draft sills and adapted to coöperate in supporting 5 said center sills independently of said draft sills.

29. In a car underframe comprising wood center sills, independent channel shaped metal draft sills in a plane below said center 10 sills and a recessed cross bearer partly below

said draft sills and adapted to coöperate in supporting said center sills independently of said draft sills.

In witness whereof I have hereunto set my hand in the presence of two witnesses.

JOHN McE. AMES.
